UNITED STATES PATENT OFFICE

157,262

CONTAINER CAP

Albert H. Jung, Flushing, N. Y., assignor to Victor
 Industries Corporation, Brooklyn, N. Y., a corporation of New York

Application May 12, 1948, Serial No. 146,324

Term of patent 14 years

(Cl. D58—26)

To all whom it may concern:

Be it known that I, Albert H. Jung, a citizen of the United States, residing at Flushing, in the county of Queens, city and State of New York, have invented a new, original, and ornamental Design for a Container Cap, of which the following is a specification, reference being had to the accompanying drawing, forming part thereof.

Fig. 1 is a top plan view of a container cap showing my new design.

Fig. 2 is a side elevational view thereof taken partially in section.

The characteristic features of the design reside in the relatively thin petals having the outermost edges thereof depending below the adjacent concave under surfaces of the petals and the spherically convex domed center part extending a substantial distance above the tops of the petals and having a series of substantially

triangular aligned projections thereon all pointing to the uppermost central point of the domed surface, all as shown in the drawing.

I claim:

The ornamental design for a container cap, substantially as shown and described.

ALBERT H. JUNG.
